ENGINE

Andre J. Meyer, Detroit, Mich., assignor to Continental Motors Corporation, Detroit, Mich., a corporation of Virginia

Application March 30, 1931, Serial No. 526,159

5 Claims. (Cl. 123—197)

My invention relates to internal combustion engines and is more particularly related to the construction and arrangement of cooperating engine parts such as the crankshaft, piston and other operating mechanisms associated therewith.

One of the objects of my invention is to provide an internal combustion engine which may be more economically manufactured by providing an engine structure which may be more compactly arranged and assembled within a crankcase of minimum dimensions thereby obtaining an engine structure of minimum weight which obviously results in a saving of material.

Another object of this invention is to construct an internal combustion engine having improved operating characteristics by providing a construction wherein objectionable "piston slap" has been eliminated.

It will be noted that the principle of my invention may be incorporated in internal combustion engines of the poppet valve type as well as those of the sleeve valve type and in the accompanying drawings both types of engines are illustrated and it will be apparent that this invention may be advantageously employed to provide a more efficient engine and an engine which may be more readily maintained in service with a minimum of labor and expense.

For a more detailed understanding of my invention reference may be had to the accompanying drawings in which the principle of my invention is illustrated with various types of engine structures, and in which:

Figure 1 is a vertical transverse sectional view 35 of a sleeve valve internal combustion engine constructed in accordance with my invention.

Figure 2 illustrates by a diagram the curves representing the side thrust of the piston relative to the cylinder of an internal combustion engine 40 of the standard type as plotted against crankshaft travel.

Figure 3 is a similar diagram showing the side thrust in an engine in which the crankshaft is offset from the central longitudinal plane of the engine in a direction opposite to crankshaft rotation.

Figure 4 is a similar diagram illustrating the side thrust of an engine having a crankshaft offset from the central longitudinal plane of the engine in the direction of crankshaft rotation.

Fig. 4a is a diagrammatic plan view illustrating the effect between the crankshaft axis and the longitudinal plane of the engine containing the axes of the engine cylinders, and

Figure 5 is a vertical transverse sectional view

through an internal combustion engine of the poppet valve type.

Referring more particularly to the engine construction illustrated in Figure 1 it will be noted that I have employed a cylinder block 10 having 60 one or more cylinders 11 in which sleeve valve means 12 may be assembled. The cylinders and parts illustrated are typical of each cylinder of the engine. The cylinder head 13 is secured to said cylinder block and is provided with a re-entrant head portion 14 depending within the cylinder and spaced therefrom to provide a sleeve pocket 15 adapted for receiving the upper end of said sleeve valve means 12. The cylinder structure is provided with intake and exhaust ports 70 16 and 17 respectively and the sleeve valve means is provided with intake and exhaust ports 18 and 19 adapted for cooperative action with said cylinder ports on operating the said sleeve valve means.

In order to illustrate the principle of my invention I have chosen as a means of illustration an engine of the single sleeve valve type in which the sleeve valve is given a combined reciprocating and oscillating movement relative to the cylinder and sleeve axes whereby any point on said sleeve traverses a closed path. Movement is imparted to this sleeve by means of a wobble valve shaft

20 in a well known manner suitable arms 21 being employed for transmitting the desired movement 85 from the wobble shaft as close to the sleeve valve as possible without interfering with the engine crankshaft 51. It will be noted that the wobble shaft illustrated in Figure 1 is located at a point

above the horizontal engine plane containing the 90 crankshaft axis but only slightly offset outwardly from the vertical longitudinal plane through the ball and socket connection 22. This compact assembly is made possible by offsetting the axis of the crankshaft 51 to the opposite side of the 95 longitudinal plane of the engine containing the cylinder axis, thus making it possible to locate the axis of said wobble shaft in the manner illustrated which has been found quite essential for the efficient operation of such an engine. It is

quite obvious that this crankshaft may be offset 100 an appreciable amount and in the engine illustrated said crank shaft 51 has been offset about three-quarters of an inch. It will be apparent that the side thrust of the piston 50 relative to

the cylinder will be increased by offsetting the crankshaft as illustrated in the accompanying drawings but I find that this crankshaft may be offset the amount shown without causing excessive forces which cannot be carried by the engine

structure. A connecting rod 52 connects the piston with the crankshaft 51.

It will be noted that I offset the crankshaft to that side of the central longitudinal plane of the engine opposite to the valve shaft and it is thus possible to construct a more compact engine having a crankcase of minimum dimensions and weight. In addition to the above advantages, it will be noted that this construction facilitates the more efficient operation of an engine of the sleeve valve type by permitting the positioning of said valve shaft in a more advantageous location.

In addition to the structural advantages as described above, the offsetting of said crankshaft with respect to the central longitudinal plane of the engine in the direction of the crankshaft rotation will eliminate objectionable piston slap. The diagram in Figure 4 illustrates the side thrust of the piston 50 relative to the cylinder in one complete engine cycle. When the piston is at top dead center the side thrust is exerted against the left side of the cylinder as viewed in Figure 1 and represented in Figure 4 at 25 and marked "0". The engine has been fired prior to the time when the piston reaches top dead center and the maximum pressure rise is obtained at top dead center or immediately after. After the piston passes top dead center the side thrust is slightly increased until the piston approaches bottom dead center when said thrust is rapidly decreased. The side thrust is still directed in the same direction as the piston passes through the region at bottom dead center and the side thrust is not reversed until the crankshaft is moved through an angle of approximately 30° beyond bottom dead center. This point is designated by the reference character 26 and shows the curve crossing the center line 27 of the diagram during the compression stroke. The curve recrosses this center line twice and the final crossing is approximately 30° in advance of top dead center, this crossing being designated at 28. At the end of the compression stroke the side thrust is directed generally in the same direction before the piston reaches top dead center and after it passes top dead center. Thus on observing the diagram illustrated in Figure 4 it will be seen that the side thrust of the piston relative to the cylinder is influenced in such a manner as to apply said side thrust generally in one direction when the piston is in the region of top dead center and bottom dead center. It will be further noted that the side thrust of said piston relative to the cylinder is influenced in such a manner as to reverse the directional forces of said side thrust only when the piston lies intermediate the regions of top and bottom dead center. Furthermore, it will be noted that this side thrust is applied generally in one direction throughout the entire power stroke of the piston and said side thrust is applied generally in this same direction before the piston reaches top dead center and after the same passes beyond bottom dead center and thus there is no sudden change in the direction of the side thrust during the power stroke of the piston. By reversing the direction of the side thrust only when the piston is not in the region of top or bottom dead center it will be noted that the piston is thus made to strike the cylinder a glancing blow due to the fact that the same is travelling longitudinally of the cylinder bore at the time the direction of the side thrust is reversed. Another advantage resulting from the construction herein illustrated is that there is no abrupt change in

the direction of the side thrust from one side of the cylinder to the other, it being noted in the curve illustrated in Figure 4 how the side thrust is gradually reduced prior to and subsequent to the time the direction of said side thrust is reversed.

Figure 3 illustrates a curve representing the side thrust of the piston relative to the cylinder when the crankshaft is offset to one side of the longitudinal plane of the engine containing the cylinder axis opposite to the crankshaft rotation and illustrated in Figure 1 by the dotted line 29. In this case it will be noted that the side thrust of the piston relative to the cylinder is reversed during the power stroke of the engine designated by the curve marked "0—180°". Further, it will be noted that the direction of said side thrust is reversed when the piston is in the region of top dead center as illustrated by the diagram which shows the curve representing the side thrust crossing and recrossing the center line 30 in the region of top dead center. This curve distinctly shows that the side thrust is not applied in such a manner as to be directed generally in one direction when the piston is in the region of top dead center, and thus the reversal of the side thrust when the piston is in the region of top dead center and when the piston has no appreciable movement longitudinally of the cylinder bore will cause a very objectionable piston slap.

Figure 2 illustrates a curve representing the side thrust of a standard engine in which the crankshaft is not offset with respect to the central longitudinal plane of the engine. In this case it will be noted that the side thrust is zero when the piston is at top and bottom dead center and it will be noted that the direction of the side thrust of the piston relative to the cylinder is reversed at top and bottom dead center thereby causing an objectionable piston slap which has been generally sought to be overcome by various piston constructions which minimize the excessive clearances between the piston and the cylinder wall.

It will be noted that I have provided a piston of standard construction and have constructed my engine so as to permit the direction of the side thrust of the piston relative to the cylinder to be reversed, but my construction so influences the side thrust as to reverse the direction thereof at certain predetermined times when the said reversing of the side thrust may take place without causing an objectionable piston slap which would be audible. This control is accomplished by providing for a gradual change in directional forces and by making said change while the piston is travelling longitudinally of the cylinder bore with an appreciable speed which causes the piston to strike the cylinder with a glancing blow.

In Figure 5 I have illustrated an engine construction having a cylinder block 40 provided with a cylinder bore 41 in which a piston 42 operates, said piston being connected with a crankshaft 43 by a connecting rod 44. Said crankshaft is offset with respect to the longitudinal plane of the engine containing the cylinder axis in the direction of the crankshaft rotation. This figure illustrates an engine of the poppet valve type and shows how the camshaft 45 may be located directly below the cylinder ports since the crankshaft is offset and the camshaft occupies that space customarily allowed for the crankshaft of an engine whose axis lies in said longitudinal engine plane. The construction 150

herein illustrated permits the more compact arrangement of the cooperative parts of a poppet valve engine thereby obtaining advantages of weight and low cost as in the sleeve valve engine.

5 In Figure 1 the sleeve 12 has its inner end recessed at 12° generally above the crankshaft at the side opposite the valveshaft 20 in order to accommodate the angular travel of connecting rod 52. Likewise in Fig. 5 the cylinder 41 has its 10 inner end recessed at 41° at a corresponding relation to the valveshaft 45 and for the same purpose.

The compact arrangement made possible by the construction described above is very advantageously incorporated in a sleeve valve engine and it will be noted that the major portion of the sleeve valve 12 (Figure 1) lies intermediate the longitudinal vertical planes A and B of the engine which contain respectively the valve shaft 20 and crankshaft axes.

When I refer in the specification and claims to the crankshaft as being offset in the direction of its rotation or similar expressions I mean that relationship illustrated in Fig. 1, viz., where the 15 crankshaft is considered as rotating with a crank moving downwardly. As the crank moves downwardly it also of course moves laterally with respect to a plane longitudinally of the engine and containing the crankshaft axis and the offset is 20 in the same direction.

In Fig. 4a, X—X represents the longitudinal plane of the engine containing the axes of the engine cylinders 11 (or 41 for the engine of Fig. 5) and Y—Y represents the crankshaft axis, the 25 offset being indicated.

It will be apparent to those skilled in the art to which my invention pertains that various modifications and changes may be made therein without departing from the spirit of my invention or from the scope of the appended claims.

40 What I claim as my invention is:

1. An internal combustion engine having a cylinder block formed with a plurality of aligned cylinders, adjacent cylinders having their axes lying 45 in a common plane extending longitudinally of the cylinder block, pistons operable co-axially within the respective cylinders, and a crankshaft connected for actuation by said pistons, said crankshaft having its axis extending longitudinally of the cylinder block and offset laterally from said plane in the direction of crankshaft rotation.

50 2. An internal combustion engine having a cylinder block formed with a plurality of aligned

cylinders, adjacent cylinders having their axes lying in a common plane extending longitudinally of the cylinder block, pistons operable co-axially within the respective cylinders, and a crankshaft connected for actuation by said pistons, said crankshaft having its axis extending longitudinally of the cylinder block and offset laterally from said plane in the direction of crankshaft rotation in such a manner that tendency of said pistons to slap is opposed.

3. An internal combustion engine having a cylinder block formed with a plurality of aligned cylinders, adjacent cylinders having their axes lying substantially in a common plane extending longitudinally of the cylinder block, pistons operable co-axially within the respective cylinders, a crankshaft, and connecting rods between the crankshaft and respective pistons, said rods connecting said pistons substantially in said plane, said crankshaft having its axis extending longitudinally of the cylinder block and offset laterally from said plane in the direction of crankshaft rotation.

4. In an internal combustion engine of the sleeve valve type having a cylinder block formed with a plurality of aligned cylinders, adjacent cylinders having their axes lying substantially in a common plane extending longitudinally of the cylinder block, sleeve valve means movably associated with the respective cylinders, pistons 100 respectively operable co-axially within said sleeve valve means and said cylinders, and a crankshaft connected for actuation by said pistons, said crankshaft having its axis extending longitudinally of the cylinder block and offset laterally from said plane in the direction of crankshaft rotation.

5. In an internal combustion engine of the sleeve valve type having a cylinder block formed with a plurality of aligned cylinders, adjacent 115 cylinders having their axes lying substantially in a common plane extending longitudinally of the cylinder block, sleeve valve means movably associated with the respective cylinders, pistons 120 respectively operable co-axially within said sleeve valve means and said cylinders, and a crankshaft connected for actuation by said pistons, said crankshaft having its axis extending longitudinally of the cylinder block and offset laterally from said plane in the direction of crankshaft rotation, whereby to oppose tendency for the pistons to slap against said sleeve valve means.

ANDRE J. MEYER.
